CLAIM

The ornamental design for a financial proof machine or
similar article, substantially as shown and described.

DESCRIPTION

FIG. 1 is a front elevational view of a financial proof
machine or similar article showing our new design;
FIG. 2 is a front elevational view taken at a slightly
different angle;

FIG. 3 is a rear elevational view of the view shown in
FIG. 1; and

FIG. 4 is a rear elevational view taken at a slightly
different angle.

FIG. 3

FIG. 4
